UNITED STATES PATENT OFFICE.

JAMES WILKINSON, OF PROVIDENCE, RHODE ISLAND, ASSIGNOR TO
WILKINSON TURBINE COMPANY, A CORPORATION OF ALABAMA.

TURBINE BUCKET-WHEEL.

No. 811,985.

Specification of Letters Patent.

Patented Feb. 6, 1906.

Application filed July 3, 1905. Serial No. 268,205.

To all whom it may concern:

Be it known that I, JAMES WILKINSON, a citizen of the United States, residing at Providence, in the county of Providence and State of Rhode Island, have invented new and useful Improvements in Turbine Bucket-Wheels, of which the following is a specification.

My invention relates to improvements in the construction of buckets or intermediates 10 and the manner of mounting them on bucket wheels or drums or intermediate holders in an elastic-fluid turbine.

One object of my invention is to effect a more secure and positive jointing of the buckets to their support by providing one or more locking elements which engage both the bucket-support and the buckets and hold them together by being shrunk in place thereon. Thus as an illustrative embodiment of 15 my invention I provide a bucket-wheel with a shouldered rim or periphery upon which are mounted one or more rows of buckets having shouldered base portions. One or more retaining-rings are caused to engage the shouldered shanks of the buckets and the shouldered rim of the wheel, after which the ring or rings are shrunk, so as to securely and positively hold the buckets to the wheel. A slight clearance is left between the ring and 20 the parts engaged thereby to compensate expansion and permit the ring being slipped in place while heated.

A further object of my invention is to provide a novel form of reversible bucket against 25 which the motor fluid will act with equal efficiency when discharged against the same from either direction. The purpose of this construction is to enable a direct-action turbine to be provided with bucket elements by 30 means of which it may be reversed efficiently by reversing the flow of steam through the turbine or any part of its working passage.

My invention further comprises the details of construction and arrangement of parts 35 hereinafter more particularly described and claimed, reference being had to the accompanying drawings, in which

Figure 1 is a partial vertical sectional view through a bucket-wheel provided with my 40 improved reversible buckets and illustrating the manner of mounting the same in accordance with my invention. Fig. 2 is a top plan view of a portion of the bucket-wheel, show-

ing several of the buckets in cross-section. Fig. 3 is a view of the bucket-wheel and locking-rings with the buckets removed. Fig. 4 is a detail front elevation of one of my reversible buckets, Fig. 5 is a side elevation thereof, and Fig. 6 is a vertical sectional view along the line *x-x*, Fig. 4. Fig. 7 is a top plan view of Fig. 4.

Similar reference-numerals refer to similar parts throughout the drawings.

I have chosen to illustrate my invention as applied to a turbine bucket-wheel carrying a single row of buckets; but it will be understood that the invention is applicable for securing various bucket constructions to any type of stationary or rotatable bucket carrier. The wheel 1 is provided with a rim 2, provided with annular shoulders 3 and 4, which project beyond the sides of the wheel-body. A row of buckets 5, provided with base blocks or shanks 6, are mounted upon the rim 2 of the wheel. The shanks 6 are provided with shoulders 7 and 8, the base portion of the shank corresponding in width with the rim 2 upon which it rests. The shank 6 is preferably formed integral with the bucket, which projects on either side thereof. 75 A locking-ring 9 is provided with an annular channel 10, whose radial width slightly exceeds the combined width of the shouldered portion 7 of the shank and the shoulder 3 of the rim, over which parts the ring is set. This 80 leaves a clearance 11, Fig. 1, between the shoulders of the ring and the rim before the former is shrunk. The ring is so constructed that it engages the top of shoulder 7 and fits tightly against the under side of one wing of 85 the bucket, its width corresponding with the extent of the projection of the side or wing of the bucket to the left of the shank 6. A similar ring 12 is adapted to engage the shoulders 4 and 8 on the opposite sides of the wheel 90 and bucket shanks and the under side of the wing of the bucket projecting to the right of the shank 6. The wheel-rim thus formed corresponds in width with the impact-surface 95 of the buckets. When the parts have been assembled, as shown in Fig. 1, the rings 9 and 12 are shrunk over the bucket-shanks, thereby closing up the clearances 11 and firmly and rigidly uniting the buckets to the wheel 100 to avoid any possibility of their rattling or shaking loose or moving relatively to the 105

wheel. The retaining-rings are then securely riveted or bolted to the body portion of the wheel by means of rivets or bolts 13.

The buckets 5 are provided with two reversely-disposed concave impact-surfaces 14 and 15, to form which the bucket is reduced at its middle portion 16, from which point in both directions it increases in thickness to the central portion of the impact-surfaces 14 and 15, from which points it tapers to the side edges of the bucket. In other words, the bucket substantially corresponds in cross-sectional configuration to the combination of two similar reversely-disposed concavo-convex buckets whose adjacent side edges are formed by a narrow integral web connecting the two buckets and forming the whole into an integral reversible bucket element. The bucket portions are formed integral with the shanks 6, which constitute base-blocks whose peripheral length serves to space the buckets apart. At their outer ends the buckets are formed with integral head-blocks 17 of less width than the bucket and having squared ends which abut, so as to brace the outer ends of the buckets and space them apart. These head-blocks may be swelled by clinching their abutting edges, thus giving the sectional rim an initial strain to stiffen the buckets. As shown, the passage between the buckets is substantially S-shaped and of equal cross-sectional area. The concavity of the faces 14 and 15 or the convexity of their respective sides of the bucket may be varied so as to vary the cross-sectional area of the passage for the fluid between buckets in any manner desirable.

While I prefer to use two locking-rings to secure the buckets in place on the bucket-carrier by shrinking them over the bucket-shanks, I desire to protect the use of only one of these locking-rings operating in this manner, the engagement of the other sides of the buckets to the bucket-carrier being effected in any of the other ways now commonly practiced. It will also be understood that this manner of securing the buckets to the carrier is independent of the specific construction of the bucket or the purpose for which it may be used.

Having thus described my invention, what I claim as new, and desire to secure by Letters Patent, is—

1. In a turbine, a plurality of buckets, a support therefor, and a locking-ring engaging said support and said buckets and adapted to hold the latter to their support by being shrunk thereon, substantially as described.

2. In a turbine, a plurality of buckets, a support upon which said buckets are mounted, two locking-rings disposed on opposite sides of the support and in engagement therewith, the said rings being adapted to engage

1 said buckets and to lock the same to said support by being shrunk, and means to fasten 65 the rings to the bucket-support, substantially as described.

3. In a turbine, a plurality of buckets, a support therefor, and means to fasten said buckets to said support by shrinking an element or elements which engage both buckets and support.

4. In a turbine, a plurality of buckets, a support therefor, a locking element which engages said support and buckets and is adapted to lock these parts together by being shrunk, and means to fasten said element to the bucket-support.

5. In a turbine, a plurality of buckets, a support therefor, locking elements which engage said support and buckets and are adapted to lock these parts together by being shrunk, and means to fasten said elements to the bucket-support.

6. A turbine bucket-wheel formed with a flanged rim portion, buckets having flanged base portions engaging said rim, and a ring formed with shoulders adapted, when the ring has been shrunk to engage the rim of said wheel and the flanged bases of said buckets, a clearance being left between the ring-shoulders and buckets or rim to provide for this shrinkage, and means to secure said ring to said wheel.

7. A turbine bucket-wheel, buckets, said wheel and buckets having portions adapted to be engaged by locking means, said locking means comprising two rings adapted to be shrunk into engagement with the wheel and buckets, and bolts or rivets for securing said rings to the wheel.

8. In a turbine, a bucket-support, and buckets thereon having reversely-disposed impact-surfaces, the reverse side of the bucket opposite a concave impact-surface being convex and of greater thickness than the middle portion of the bucket.

9. In a turbine, a bucket formed on a double curve, thickest at the heads of the curve and tapering to the sides and center.

10. In a turbine, a plurality of buckets, and a support therefor, substantially as described.

11. In a turbine, a bucket having duplicate reversely-disposed impact-surfaces in the form of double curves, meeting at the bucket edges and arranged so as to leave metal of varying thickness between them at different parts of the bucket.

In testimony whereof I have hereunto set my hand in presence of two subscribing witnesses.

JAMES WILKINSON.
